UNITED STATES PATENT OFFICE

2,655,094

STORM SHUTTER

Charles C. Guercio, Smithtown Branch, N.Y.

Application June 1, 1949, Serial No. 96,552

5 Claims. (Cl. 98—99.8)

1

The present invention relates to new and useful improvements in window shutters or ventilators, and more particularly to a window shutter composed of vertically swinging louvers or slats operated by a raising and lowering movement of a sliding sash.

An important object of the invention is to provide a window shutter mounted in position in a window frame under a vertically sliding sash and including a plurality of vertically swingable louvers or slats pivoted in the frame in an off-balanced position to normally hold the slats or louvers in a downwardly inclined closed position and providing operating means for the slats or louvers positioned under the sash for swinging the slats or louvers into a raised or open position by a downward movement of the sash.

A further object of the invention is to provide an adjustable frame for the shutter for mounting in window frames of various sizes.

A still further object is to provide a window shutter provided with a screen.

A still further object is to provide a device of this character of simple and practical construction, which is efficient and reliable in operation, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view with parts broken away and shown in section and showing the shutter mounted in position in a window;

Figure 2 is a horizontal sectional view taken on a line 2—2 of Figure 1;

Figure 3 is an enlarged vertical sectional view taken on a line 3—3 of Figure 1;

Figure 4 is a fragmentary vertical sectional view showing the louvers or slats in a lower or closed position;

Figure 5 is a fragmentary perspective view of one side of the window shutter, and

Figure 6 is a perspective view of the sash lock.

Referring now to the drawings in detail wherein, for the purpose of illustration I have disclosed a preferred embodiment of the invention, the numeral 5 designates a shutter frame including side frame members 6, an inverted channel-shaped bottom frame member 7, and a head or top frame member 8, said frame members being

2

suitably secured to each other in a rigid position. The bottom frame member 7 is fitted over a block 9 suitably secured on the sloping surface 10 of a window sill 11 to support the bottom frame member 7 in a horizontal position.

The outer edge of head or top frame member 8 is formed with an upstanding flange 12 having downwardly curved hooks or hangers 13 extending over the upper edges of a pair of horizontally adjustable side wings 14 of angle construction to provide a front flange 15 and rearwardly projecting side flanges 16. Brackets 17 are suitably secured to the inner edge of bottom frame member 7 and on which the lower edge of wings 14 are slidably supported. Handles 18 are secured to wings 14 to slidably adjust the latter.

The wings 14 at each side of frame 5 are positioned at the sides of a window frame 19 between the sash guides 20 for a lower window sash 21 and are connected to the sides of shutter frame 5 for inward and outward sliding adjustment by means of a plurality of flat bars 22 welded or otherwise suitably secured to the inner surface of flange 16 of the wings and projecting horizontally inwardly through slots 23 in the side frame members 6. The free ends of bars 22 are formed with T-heads 24 to limit outward sliding adjustment of the wings 14 with respect to the frame 5.

A plurality of louvers or slats 25, preferably constructed of glass or other suitable plastic material, are provided with pins or trunnions 26 embedded in the side edges thereof and are pivotally supported in recesses 27 at the inner lower ends of inclined slots 28 extending inwardly from the outer edges of the side frame members 6, the louvers being vertically swingable about horizontal axes.

The pins 26 are positioned adjacent the inner edges of the louvers or slats 25 and cause the outer edges thereof to counterbalance the louvers to swing downwardly by the weight of the louvers or slats into a closed position.

The rear edges of louvers or slats 25 are formed with notches 29 in which a vertical connecting bar 30 is positioned and connected to the louvers or slats by brackets 31 pivotally connected, as at 31', to the bar 30 for simultaneously raising and lowering the louvers. The lower end of bar 30 is connected to the lower frame member 7 by means of a pivoted link 32 and bracket 33 and a short horizontal arm 34 is rigidly secured to the upper end of bar 30 and to which the lower end of a rod 35 is secured. The rod 35 extends upwardly through a slot 36 in the head or upper

frame member 8 and is provided at its upper end with a horizontal plate 37 secured to the under side of an extensible, sectional, hollow box 38 member positioned immediately under sash 21 and having a solid reinforcing block 39 loosely placed therein.

Rods 40 extend downwardly at each end of box 38 through openings 41 in the bars 22 to slidably adjust the sections of box 38 member inwardly and outwardly by the adjustment of wings 14.

A screen 42 is suitably secured to the front edge of frame 5 behind front flange 15 of wings 14.

A shield 43 extends downwardly at the outer edge of upper frame member or head 8 to exclude rain from entering the top of frame 5 above the uppermost louver 25 when the louvers are closed.

In the operation of the device, wings 14 are adjusted inwardly or outwardly to position the same in the sash guide for a lower window sash and the sash 21 lowered on the box 38 member to force operating bar 30 downwardly and to raise the outer edges of louvers 25 into a horizontal open position, as shown in Figure 3, the louvers being held in their raised position by the weight of the sash. The shutter is constructed of a size to permit slight raising and lowering movement of the sash, after the shutter is placed in the window under the sash, and a raising movement of sash 21 to relieve box 38 member of its weight will enable the louvers 25 to swing downwardly into their closed position, as shown in Figure 4.

In order to prevent unauthorized persons on the outside of the window from sliding wings 14 inwardly to remove the shutter, I provide a vertical locking pin 44 slidably positioned in an opening 13a in each upper hanger 13 and projecting upwardly through an opening 45 in a U-shaped locking plate 46 positioned horizontally and with a longer end 46' overlying the bottom rail 47 of sash 21 to lock said sash against upward movement and with its other shorter end 46'' end received in a horizontal socket 48 secured to window frame 19. The upper end of pin 44 is bent angularly to form a handle 49 and to hold the pin in plate 46. The lower end of pin 44 enters a notch 50 in the upper edge of wing 14.

Each wing 14 is provided with one of the locking pins 44.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. In combination with a window frame having a vertically sliding window sash therein, a window shutter including a shutter frame fitted in the window frame below the sash and having a top frame member, a plurality of louvers pivoted in the shutter frame for swinging about horizontal axes into open position and counter-

balanced for swinging into closed position, and means for swinging said louvers into open position operative by downward sliding of said sash including a horizontal member interposed between said top frame member and the sash and supporting the sash in partly open position and movable downwardly against said top frame member by downward sliding of said sash against the same, and operating connections between said horizontal member and said louvers.

2. The combination according to claim 1, including side wings for said shutter frame, bars on said wings slidably connecting said wings to said shutter frame for adjustment of said wings horizontally to fit said shutter frame in said window frame, said horizontal member comprising slidably connected sections relatively adjustable to extend said horizontal member to fit in said window frame, and connections between said bars and said sections for adjusting the sections to extend said horizontal member by adjustment of said wings.

3. The combination according to claim 2, said connections comprising rods on said sections vertically slidably in said bars to provide for vertical movement of said horizontal member relative to said bars.

4. The combination according to claim 1, including side wings for said shutter frame, bars on said wings slidably connecting said wings to said shutter frame for adjustment of said wings to fit said shutter frame in said window frame, and means for locking said sash against raising and said wings to said window frame when adjusted.

5. In combination with a window frame having a vertically slidable sash therein, a shutter frame mounted in said window frame below said sash, horizontally adjustable wings mounted on the sides of said shutter frame for fitting said shutter frame in said window frame and provided with notches therein, a vertically movable member above the shutter frame compressible by downward sliding of said sash against the same, louvers pivoted in said shutter frame for swinging into closed position, operating connections between said member and louvers for swinging said louvers by depression of said member, a pair of sockets secured to said window frame at opposite sides of the same, a pair of plates engaged in said sockets and overlying said sash at opposite sides thereof to prevent upward sliding of said sash, and pins in said plates engaging the notches in said wings to lock said wings in adjusted position.

CHARLES C. GUERCIO.
